UNITED STATES PATENT OFFICE.

CARL JULIUS LJUNGGREN, OF PROVIDENCE, RHODE ISLAND.

HOSE-SUPPORTER.

No. 852,335.

Specification of Letters Patent.

Patented April 30, 1907.

Application filed November 27, 1906. Serial No. 345,333.

To all whom it may concern:

Be it known that I, CARL JULIUS LJUNGGREN, a subject of the King of Sweden, residing at Providence, in the county of Providence and State of Rhode Island, have invented certain new and useful Improvements in Hose-Supporters, of which the following is a specification.

My invention relates to improvements in what may be termed hose supporters or garters. Its objects are to greatly simplify the construction, the fastening proper being in a single piece; to render it easy of application; to lessen cost of manufacture; and to provide for efficiency in its holding action.

Said invention consists of certain structural features or instrumentalities substantially as hereinafter fully disclosed and specifically pointed out by the claims.

In the accompanying drawing illustrating the preferred embodiment of my invention—Figure 1 is a perspective view thereof. Fig. 2 is a like view of the same as applied to a hose or stocking for practical use. Fig. 3 is a detail side view of the clasp-member or fastening proper.

In the disclosure of my invention, I stamp or form, from metal of plate-like character and sufficient stiffness or rigidity for practical purposes, in a single piece, a clasp-member 1. This latter is principally of the general outline disclosed, slightly tapering upward and terminated in a disk-like formation 2, at its upper end, and accordingly flaring slightly downward, and is slotted or bifurcated as at 3 from its lower end upward a suitable distance, thus providing it with two arms or branches 4, 5, standing a slight interval apart and having their outer edges each equipped with a series or number of teeth or corrugations 6 for greater effectiveness in using the same as will be seen later. The disk-like formation or upper end 2 is provided with opposed, oppositely inclined slots 7; and through one of these slots is adjustably looped one end of a preferably elastic band or garter 8 for application to the leg, its other end being adjustably looped through and equipped with a hook or clip 9 adapted for engagement with the other of said slots this being effected, of course, after encompassing the leg with said band or garter.

In applying the device for use the clasp proper 1 is suitably held in the right hand, as

judgment would suggest, to dispose it, the 55 clasp, close to the inner or shin side of the leg, just above the top edge of the stocking leg with the thumb resting against said inner side of the leg. Next grasp said edge of the stocking or hose leg with the other hand and 60 stretch it a little and place the arms or branches 4, 5 astride of said stretched edge, so that the arm or branch 5 will come between the stocking or hose leg and the leg of the wearer, the arm 4, of course, standing 65 upon the outside of the hose; then turn the hand yet grasping the clasp or member 1, to the right until the latter rests flat upon the shin-bone. Next pass the band or garter 8 around the calf of the leg and engage its hook 70 or clip 9 with the required slot in the upper end of the clasp-member 1. The arms or branches, in being turned or reversed side for side, as has been effected by the above noted manipulation of the same, will, of 75 course, have infolded the stocking or hose leg upon itself and upon said branches or arms, whose teeth will also result in more effectively gripping the hose, and accordingly have interlocked the latter with said stocking-leg, thus effectively securing it until the garter may be removed, which may be effected by simply disengaging the hook or clip 9 from its retaining slot when the clasp may be readily detached from the hose without any 80 difficulty whatever.

I claim—

1. A device of the character described, embracing a clasp provided with engaging arms or branches requisitely spaced apart, to 90 receive between them the object to be engaged and adapted for stressing the latter and means effective for the retention of said clasp in position under stress.

2. A device of the character described, 95 embracing a clasp provided with engaging arms or branches, separated a slight interval apart and having its head-end provided with opposed slots, and a band or garter proper having one end looped through one slot and its other end equipped with a hook or clip effective for engagement with the other slot.

3. A device of the character described, 100 embracing a clasp member provided with engaging arms or branches separated a slight interval apart and equipped upon their outer lateral edges with teeth or corrugations, said

clasp-member also having its head end provided with opposed inclined slots and a band or garter proper having one end looped through one of said slots and its other end 5 adjustably looped through, and equipped with a clip or hook effective for engagement with the other of said slots.

In testimony whereof I affix my signature, in presence of two witnesses.

CARL JULIUS LJUNGGREN.
